UNITED STATES PATENT OFFICE.

CHARLES H. BOECK, OF JACKSON, MICHIGAN, ASSIGNOR TO WHITE FROST REFRIGERATOR COMPANY, OF JACKSON, MICHIGAN, A CORPORATION OF MICHIGAN.

WATER-COOLER FOR REFRIGERATORS.

1,353,018.

Specification of Letters Patent. Patented Sept. 14, 1920.

Original application filed September 28, 1917, Serial No. 193,752. Divided and this application filed August 6, 1918. Serial No. 248,514.

To all whom it may concern:

Be it known that I, CHARLES H. BOECK, a citizen of the United States, residing at Jackson, in the county of Jackson and State of Michigan, have invented certain new and useful Improvements in Water-Coolers for Refrigerators; and I do hereby declare the following to be a full, clear, and exact description of the invention, such as will enable others skilled in the art to which it appertains to make and use the same.

This invention relates to water coolers, and more particularly to a water cooling device designed and adapted to be placed in the ice chamber of a refrigerator so that the same refrigerating agent as that employed in an ordinary ice-box for refrigerating purposes may be used to cool drinking water by placing blocks of ice on such cooling device.

The main object of the invention is to provide a simple, inexpensive and efficient water cooling device of the character referred to that may form a false bottom for the ice chamber and on which cakes of ice may be placed and which shall possess the requisite strength to withstand the shocks due to careless placing or throwing ice thereon. Other objects are to provide a water cooler of the character referred to having a small cooling chamber whereby only a small quantity of water may be kept cool and drawn off from time to time as desired for drinking, together with means for connecting the cooler with a source of water supply for automatically replenishing the cooler as its contents are drawn off, thus reducing the ice consumption which may occur in increasing proportion where large quantities of the reserve water are fed into the cooler, and further to adapt the device to effectually cool a small quantity of water for drinking purposes commensurate with its size without an added cost for additional quantities of ice.

The invention will first be hereinafter more particularly described, with reference to the accompanying drawings, which form a part of this specification, and then pointed out in the claims at the end of the description.

In said drawings:

Figure 1 is a plan view of my improved

water cooling device; parts being broken away to show the interior construction; 55

Fig. 2 is a transverse vertical sectional view, taken on the line 2-2 of Fig. 1, and,

Fig. 3 is a detail sectional view of the clean-out plug.

Referring to said drawings, in which the same reference letters are used to denote corresponding parts in different views, the letter A, may denote a water receptacle composed of a flat circular metallic bottom plate or disk a , and a similar top plate a^1 , 65 the latter having a depending circumferential flange a^2 , which has its lower edge turned outwardly to form an annular projection or flange a^3 , adapted to rest upon the bottom plate a , and clamped thereto by bending the edge of the latter plate back upon itself, so as to overlie the edge of the flange a^3 , as shown more clearly in Fig. 3 of the drawings, and thus form a watertight joint, said joint being preferably sealed by soldering or otherwise to prevent leakage. The top plate a^1 , is preferably corrugated to provide a channeled surface to permit the water from the melting ice to run off into an ordinary discharge or refuse pipe (not shown). The vessel A, may be constructed of any suitable material, and of any desired shape and size, according to the shape and size of the ice chamber in which it is to be used, but preferably galvanized steel or sheet metal plates of circular form are employed, to form a shallow receptacle of circular form adapted to fit within a circular ice chamber and within which the water to be cooled may circulate in contact with the under surface of the top plate on which the blocks of ice rest. Between the top and bottom plates a and a^1 there is placed a partition B, which may consist of a metal plate placed edgewise between said plates a and a^1 , and having top and bottom flanges b and b^1 which may be soldered or otherwise secured to said plates, 90 so as to divide the interior of the vessel into an inlet compartment A^1 , and an outlet compartment A^2 , the latter being preferably considerably larger than the former to more effectually cool the water circulating therethrough before it is drawn off. In order to effect a circulation of the water within the 100 cooling chamber, and to prevent its with-

105

drawal on entering the chamber or until it has had sufficient time to be cooled by contact with the cooling surface of the top plate on which the cooling medium rests, 5 one end of said flanged metal plate B, is secured to the inner circumferential wall or flange a^2 , of the cooling chamber between the inlet C, to said chamber and the outlet C¹ therefrom, and in such manner as to 10 form a sealed joint, while the other end of said partition terminates a short distance from the inner circumferential wall of the cooling chamber, so as to provide an opening through which water may pass around 15 the partition from the smaller into the larger compartment, and thus cause the water entering the inlet C, to circulate around the smaller compartment and pass thence into and through the larger compartment, wherein it is thoroughly cooled, and 20 to prevent the water from being drawn off before it has circulated through both compartments of the cooling chamber and become thoroughly cooled.

25 On opposite sides of the partition B, at that end thereof which is joined to the inner circumferential wall of the cooling chamber, openings are provided through the flange a^2 , and in one of said openings is secured a nipple C, adapted for connection through the refrigerator wall with a supply pipe through which water from a bottle or other source of supply supported preferably 30 on the outside of the refrigerator, may flow into the smaller compartment of the cooling chamber, and in the opening on the opposite side of said partition is attached a nipple C¹, adapted for connection through the refrigerator wall with a spigot on the outside 35 of said wall, whereby the water may be drawn off from time to time and replenished in the manner indicated in my application Serial No. 193,752, on which Patent No. 1,292,573 issued January 28, 1918, and of 40 which this application is essentially a division. In the circumferential wall of the cooling chamber, adjacent that end of the partition which terminates short of said wall, an opening D, is formed through which 45 a wire may be inserted on either side of the partition for raking and cleaning out any substance, or foreign matter, that may accumulate in the cooling chamber, such opening being normally closed by a suitable plug 50 or stopper d, screwed into a nut d¹, which may be soldered or otherwise secured to the outer circumferential wall of the cooler. Said plug may be formed with an angular extension d², for attaching a wrench, if desired, for unscrewing or screwing it into 55 place.

Having thus described my invention, what I claim as new and desire to secure by Letters Patent of the United States, is:—

65 1. A water cooler adapted for use as a

false bottom in the ice chamber of a refrigerating apparatus for supporting blocks of ice thereon, said cooler comprising a shallow receptacle having inlet and outlet passages through its outer wall and having a partition therein extending across the receptacle at one side of its center from between said inlet and outlet to the opposite side thereof so as to form a large and a small compartment separated by said partition, a water 75 passage being provided at the end of said partition remote from said inlet and outlet for the circulation of water around the partition and through both compartments.

2. A water cooler adapted for use as a 80 false bottom in the ice chamber of a refrigerating apparatus for supporting blocks of ice thereon, said cooler comprising a shallow receptacle having inlet and outlet passages through its outer wall and having a partition therein extending across the receptacle at one side of its center from between said inlet and outlet to the opposite side thereof so as to form a large and a small compartment separated by said partition, a water 85 passage being provided at the end of said partition remote from said inlet and outlet for the circulation of water around the partition and through both compartments, and a clean-out opening through said wall adjacent said passage for the insertion of a 90 tool for cleaning out said compartments.

3. A water cooler adapted for use as a false bottom in the ice chamber of a refrigerating apparatus for supporting blocks of 100 ice thereon, said cooler comprising a shallow receptacle composed of a substantially circular top plate having a depending circumferential annular flange, said flange having its lower edge outwardly turned and a correspondingly shaped bottom plate having a backwardly turned circumferential edge overlapping the outwardly turned edge of said top plate, whereby the two plates are firmly secured together with a sealed joint, 105 said annular flange having an inlet and an outlet opening therethrough, and a partition plate at one side of the center of the receptacle secured at one end to said flange between said inlet and outlet openings and 110 extending across to near the opposite side of the receptacle so as to provide a water passage between its free end and said flange.

4. A water cooler adapted for use as a false bottom in the ice chamber of a refrigerating apparatus for supporting blocks of ice thereon, said cooler comprising a shallow receptacle composed of substantially circular top and bottom plates, one having a circumferential annular flange with inlet and outlet 120 openings therein and an outwardly turned edge and the other having its edge turned backwardly and overlapping said outwardly turned edge of the other plate for securing the two plates together, and a partition plate 125

having one end secured to said annular flange between said inlet and outlet openings and extending across the receptacle and terminating near the outer wall thereof so 5 as to provide a water passage around the partition between its free end and said outer wall.

5. A water cooler adapted for use in the ice chamber of a refrigerating apparatus 10 comprising top and bottom plates of circular form separated by an annular circumferential flange on one plate secured to the periphery of the other plate, and a partition separating the space between said plates 15 into two compartments of unequal size, said partition having at one end a water passage adjacent the encircling wall of the receptacle, an opening being formed through said wall adjacent said passage for the insertion 20 of a tool for cleaning out said compartments, and means for closing said opening.

6. A water cooler adapted for use in the ice chamber of a refrigerating apparatus

comprising a shallow receptacle of circular form having a partition therein separating 25 the water space into two compartments, a water passage being provided at one end of said partition adjacent the encircling wall of the vessel, and inlet and outlet openings on opposite sides of the other end of said 30 partition, together with means for connecting said inlet and outlet with a source of water supply and a discharge spout through the body of the refrigerator, a clean-out opening being formed through said encircling wall adjacent said water passage for the insertion of a tool for cleaning out said compartments, and means for closing said 35 opening.

In testimony whereof I affix my signature 40 in the presence of two witnesses.

CHARLES H. BOECK.
